UNITED STATES PATENT OFFICE.

WILLIAM J. BEST, OF CLEVELAND, OHIO.

GAS-STOVE.

1,379,957.

Specification of Letters Patent.

Patented May 31, 1921.

Application filed August 18, 1917, Serial No. 186,845. Renewed September 25, 1920. Serial No. 412,894.

To all whom it may concern:

Be it known that I, WILLIAM J. BEST, a citizen of the United States, and residing at Cleveland, in the county of Cuyahoga and State of Ohio, have invented a new and Improved Gas-Stove, of which the following is a specification.

This invention relates to that class of gas stoves in which the broiling chamber is below the oven, and its object is to provide a novel construction for the lower part of the oven which will insure a comparatively high temperature therein and will prevent this temperature in the bottom of the oven being changed to a marked extent whenever the door of the oven is opened.

This invention consists in combination with a broiling chamber and an oven mounted above the broiling chamber and adapted to be heated by means of the burners in the broiling chamber, of a heat insulating medium between the bottom of the oven and the broiling chamber so that the heat of the burners will not be localized at the bottom of the oven. It further consists in so forming the lower part of the oven as to provide an air space, the top of which is level with the door when in open position. It further consists in providing an oven with a foraminous shelf which will be level with the door when that is opened and also level with the top of the air space in the bottom of the oven.

In the accompanying drawings Figure 1 is a vertical section in perspective of this improved stove. Fig. 2 is a vertical section of the side wall at and just above the line of the burners.

Similar reference characters refer to like parts in both views.

This stove is formed by mounting the baking oven 1 above the broiling chamber 2 so that the same burners will answer for both. The back of the stove is preferably formed of plates 3 and 4 which may be continuous from the bottom of the broiling chamber to the top of the oven. The bottom of the broiling chamber is preferably formed of two plates 5 and 6 and plates 7 and 8 separate the oven from the broiling chamber, between which plates may be a layer 11 of asbestos, or mineral wool, although a simple air space may be found sufficient. The air spaces between these several pairs of plates may be sealed or not as desired. The sides of the oven and broil-

ing chamber are also formed of pairs of spaced plates as shown in Fig. 2, the outer plates 9 being imperforate and the inner plate 10 being formed with a series of openings, the lower side openings 12 admitting air to the broiling chamber from the open lower end of the space between these plates 9 and 10 into which the air may enter through openings 13. Opposite the ends of the broiling burners 14 are other openings 15 through which heated air and burnt gases may pass from the broiling chamber into the passage formed by the plates 9 and 10, which air and gases flow from this passage into the oven through the opening 16. From the oven the heated air and burnt gases may pass upwardly to the space between the plates 18 and 19 through the holes 20, shown in Fig. 1, and from this space the heated air and burnt gases may pass to the space between the plates 19 and 21 through the opening 22 near the front plate 23 of the stove. From this space between the plates 19 and 21 the air and gases will pass up into the chimney 24. It will thus be seen that the burners 14 are used for both the broiling chamber and the oven, for either or for both at the same time.

Ordinarily the receptacles for the food in the oven will rest on the open-work shelf 25 carried by the channels 26 secured to the sides 10 of the oven. A front plate 27 extends up from the bottom 7 of the oven to the height of this shelf 25 and the door 28 of the oven is so pivoted that when it is open as shown in Fig. 1, it will be level with the shelf 25 and with the top of the front plate 27. This results in an air space between the shelf 25 and the bottom plate 7 of the oven, which is of great value as hot air will remain undisturbed below the shelf 25 for a considerable period of time after the door 28 is opened.

It will be observed that the walls surrounding this air space between the shelf 25 and the bottom 7 are entirely imperforate and that there is no opportunity for transverse drafts of air in this air space. Where such drafts are possible, an amount of cold air accumulates below the shelf 25 and remains there for a considerable period of time, being unaffected to a great extent by the hot air entering through the side opening 16. By preventing any circulation of air below the shelf 25, a very much more effective oven is produced. The location of

the broiling burners 14 immediately below the plates 7 and 8 insures proper heating of the plate 7, although that may be insulated from the plate 8 by means of a blanket 5 11 of fibrous asbestos or mineral wool, or even by a dead-air space alone. This results in an even heating of the bottom of the cooking utensils resting upon the shelf 25, which is of great advantage in baking bread 10 and other flour products.

I claim:

1. In a gas stove, the combination of a broiling chamber, an oven mounted above the broiling chamber, burners mounted in 15 the broiling chamber, passages for conducting heated air and burnt gases from the top of the broiling chamber and discharging them into the sides of the oven, a door opening for the front of the oven a distance above 20 the bottom thereof, a shelf mounted in said oven level with the bottom of the door opening and a door hinged to the oven and adapted to swing down level with said shelf, the walls and bottom of the oven below the 25 bottom of the door opening being imperforate.

2. In a gas stove, the combination of a broiling chamber, an oven above the broiling chamber, a heat insulating partition constituting the bottom of the oven and the 30 top of the broiling chamber, broiling burners mounted below the partition, a shelf in the oven spaced a distance from said partition, the front of the oven extending up to said partition, a door hinged at its lower 35 edge to the front of said oven and adapted to swing down to a horizontal position level with said shelf, and a passage for burnt gases and heated air extending from the top of the broiling chamber to an opening in the 40 side of the oven above said shelf.

3. A stove comprising a broiling chamber, an oven mounted above the broiling chamber and having a door opening, a single set of burners in the broiling chamber, passages 45 extending from openings in the sides of the broiling chamber to openings in the sides of the oven, and a shelf in the oven level with the bottom of the door opening and so spaced above the bottom of the oven as to 50 leave an air space between them.

WILLIAM J. BEST.
